DISPENSING UNIT FOR A POWDERED MATERIAL CONTAINER

Marc H. Sessions, Los Angeles, Calif., assignor to United States Borax & Chemical Corporation, Los Angeles, Calif., a corporation of Nevada

Application September 10, 1958, Serial No. 52,603

Term of patent 14 years

(Cl. D52—2)

Fig. 1 is a perspective view of a dispensing unit for a powdered material container showing my new design; the broken lines showing the container are for illustrative purposes only;

Fig. 2 is an elevational view of the bottom; and

Fig. 3 is a side view.

I claim:

The ornamental design for a dispensing unit for a powdered material container, as shown and described.
